WARNING DEVICE AND SYSTEM FOR FLAME FAILURE

William J. Hardesty, Delmont, Pa., assignor, by mesne assignments, to Tele-Flame, Inc., Latrobe, Pa., a corporation of Pennsylvania

Filed Jan. 17, 1967, Ser. No. 609,886
11 Claims. (Cl. 335—156)

ABSTRACT OF THE DISCLOSURE

A warning device for flame failure employing a thermally-energized electric magnet and a magnetic contact plate to be magnetically held in a forward position by the magnet upon heat-induced energy thereto. An operating stem supports the contact plate for moving the plate into and out of engagement with the magnet.

The illustrated embodiment of the invention utilizes a thermostatic or thermal means which has a pilot flame part that may be used with a main heating burner for a hot water boiler or other apparatus that is to be heated by a fluid type of fuel, such as gas, oil and the like. The thermal means employed may be a commercial means, such as provided by Honeywell or Robertshaw-Fulton Controls Company, see for example, the Grayson unit TS-7 sold by Robertshaw-Fulton. Such a means employs thermocouple metals for generating a small thermionic current when it is heated by the flame of a burner to energize a holding electro magnet. Make and break electrical switch means is used with thermal means to provide a warning signal when the flame goes out through deenergization of the electro magnet and to reset the thermal means when heat is again applied thereto. The switch means is manually moved to an open and resetting position and, upon release after a resetting operation, remains in an open position until the electro magnet is deenergized to release a hold plate and close switch contacts.

The device of the invention may be used to give warning to the occupants of a dwelling or building of the failure of a heating agency and particularly, of a flame type of heating agency, so that immediate steps will be taken to remedy the deficiency and promptly reinstitute proper operation of the heating medium. It will be appreciated that failure may be due to clogging of the fuel line, a blast of air, insufficient fuel or insufficient oxygen for supporting the flame.

Brief summary of the invention

Heretofore, it has been customary to employ thermostatic controls employing a thermocouple and an electro magnet for the purpose of shutting-off the supply of fuel to a main burner or heating element if, for example, the pilot flame fails. This has the disadvantage that unless periodic inspections are being made of the boiler or other means being heated, that the householder or building maintenance man has no indication of the failure until the adverse effects, for example, lack of heat, are, after a period of time, evident to him. The present invention deals with an alarm or warning apparatus whereby immediate indication of flame or heat failure is given.

It has thus been an object of my invention to provide a thermal operating device that will immediately transmit a warning signal upon the failure of a heating unit or the like;

Another object has been to devise a new and improved device for utilization in connection with a heating means, such as a fuel burner, which can be reset for each operation of the burner and will be released to close switch

2

contacts and energize an alarm system upon a failure of the burner or the extinguishing of its flame;

A further object of the invention has been to devise a simple, efficient, effective and inexpensive thermal electrical switch device for giving warning of the failure of a flame or heat source;

These and other objects of the invention will appear to those skilled in the art from the illustrated embodiment and the claims.

10

Description of the drawings

In the drawings, FIGURE 1 is an exploded view in elevation and partial section of parts employed in constructing an operating unit or device in accordance with the invention;

FIGURE 2 is a vertical view in elevation on the scale of and showing the parts of FIGURE 1 in an assembled relation; in this view, a pilot part of the unit has been omitted for simplicity of illustration;

FIGURE 3 is an enlarged vertical sectional view in elevation of the unit of FIGURE 2 showing the parts in a released or alarm giving operating position.

FIGURE 4 is a vertical sectional view on the scale of and of the unit of FIGURE 3 showing the parts in a preliminary resetting position, such as is manually accomplished when, for example, a pilot flame has been relit;

FIGURE 5 is a vertical sectional view in elevation on the scale of FIGURES 3 and 4 showing the relative positions of the parts of the unit after a release of the resetting means and after the thermal means has energized a holding magnet to automatically retain the unit in its reset position during the proper functioning of the heating means, such as a flame;

FIGURE 6 is a reduced somewhat diagrammatic side view in elevation showing a mounting closure in section and an operatively connected electrical alarm circuit or system for the device;

And FIGURE 7 is an end section in elevation on the scale of and of the operatively mounted device disclosed in FIGURE 6, but with the alarm circuit omitted.

45

Detailed description

FIGURES 6 and 7 show an operating system or apparatus employing the invention. In this connection, a mounting housing is shown provided with an outer closure part 11 and an angle-shaped inner mounting part 12 which is enclosed by the part 11. The mounting housing defines an upper burner compartment A and a lower compartment C within which a device 10 of the invention may be mounted for convenient operation. The part 12, as shown particularly in FIGURE 6, has an upright or vertical plate portion 12a that may be secured to a wall or structural support member by threaded bolts or screws 13; it also has a bottom, outwardly-projecting horizontal shelf portion 12b which defines a partition between the chambers A and C and serves as a mount for a pin-like or cylindrical thermal element containing part 18 that supports a pilot burner 19 at its end. An angle-shaped member 12c is shown secured, as by welding, to the shelf portion 12b for removably securing the outer closure part 11 in position thereover by means of metal screws 14. The thermal part 18 is carried within an angle-shaped base or support part 15 which is shown as having a mounting hole 15a therethrough. A mounting lug 12c projects downwardly from the shelf 12b somewhat intermediate of its width to serve as a mounting for the part 15. In this connection, a threaded bolt or set screw 15b may be inserted through the hole 15a into threaded engagement with the mounting lug 12c (see FIGURE 7).

50

55

60

65

As shown particularly in FIGURE 1, the burner base or support part 15 has a threaded gas or fluid fuel inlet fitting 16 projecting therefrom to receive an internally-threaded female coupling 17a of a gas or fuel supply line 17. The line 17 may extend to a suitable source, for example, to a meter connection of a home. The fuel supplied by the line 17 enters the base support part 15 and passes through the thermal part 18 to the pilot burner 19. Although not shown, a main burner and a water or other type of heating coil may be mounted in the compartment A, with the main burner located adjacent the pilot burner 19.

A somewhat flexible, copper-core, heat conductor line 20 is conductively connected to the part 18 and extends from the part 15 and has a slidable male coupling fitting 23. As shown particularly in FIGURE 1, the fitting 23 has a wrench flat 23a and a male threaded end portion 23b for cooperating with internal or female-threading 28a of sleeve end or socket 28 of a fitting 27 that is mounted on a front enclosure disk or flange 26. The end of the heat conductor line 20 is provided with a terminal plug end 21 to which its copper core is secured and with a washer 22 that cooperates with the fittings 23 and 27.

As shown particularly in FIGURES 3 and 4 of the drawings, the terminal plug end 21 is adapted to fit within the open end of the socket 28 of the fitting 27. Both the plug end 21 and the socket 28 are of a highly heat conductive metal, in order that micro current generated by the application of heat energy to thermal elements of the part 18 will be transmitted along the conductor line 20, through the plug end 21 and the part 27 to a U-shaped electro magnet 30. The magnet 30 is secured to the flange or closure disk 26 and made an integral part of the fitting 27. The poles of the magnet 30 may be suitably wound with copper conductor wire 31 so as to pick up the current generated by heat energy and energize backwardly-projecting contact faces or ends 30a of the magnet 30. The fitting 27 has an external threading 27a to removably-receive a mounting nut 29 which as shown, for example, in FIGURE 3, is employed to secure the fitting on an outer or secondary, hollow front housing 40.

The electro magnet 30 projects backwardly within a hollow or shell-like first, inner or primary front housing 25 and is secured in position with respect thereto by a turned-in front rim edge 25a of the housing that engages the end closure disk or flange 26. The inner or first housing 25 as well as the outer or second housing 40 may be of a suitable non-magnetic, electrically-conductive material, such as copper, aluminum, or brass.

The outer or second housing 40, also of hollow shape, has a front flange or turned-in rim 40a which fits over the front rim edge 25a of the inner housing 25 and is removably-secured in place by the nut 29 to project backwardly beyond a closed back end wall 25b of the housing 25 and receive a front end portion of a back housing 42 therein. The back housing 42 is also of hollow construction, is of a non-conductive material, such as resin, wood, etc., and has a mounting portion of reduced diameter 42a that is adapted to be removably-secured endwise in position within the outer front housing 40 in abutment with the back end of the inner housing 25 by set screws 41.

An operating stem 36 is slidably-positioned for axial movement within the closed back end wall 25b of the inner front housing 25 and its front end carries a magnetic contact or metal hold plate or disk 35 thereon. A magnetic part or member as mentioned herein, is a member which is of iron or other suitable material that is subject to magnetic holding attraction, such as exerted by energization of the electro magnet 30.

The operating stem 36, as shown in FIGURES 3, 4 and 5, extends at its back end portion into a front chamber portion of the hollow back housing 40 and cooperates with a reset means in the nature of a manual push or operating stem 47 that is operatively-carried for sliding or axial endwise movement within the back end portion of the back housing 40. The operating stem 36 is also of a good elec-

trically conductive metal, such as brass, copper or aluminum, and preferably the former. The back end of the stem 36 carries an integral or secured-on disk or mounting flange 37 and a first switch contact means in the form of a flange or disk 37a of a good electrically conductive metal. A good electrically conductive set screw 37b having a flat head end is employed for removably-securing the first contact switch means 37a on the stem 36 in abutment with the flange 37. Electric current is carried from a connector means or terminal, such as a threaded binding screw and washer assembly 51, through the housing 40 to the housing 25, and from the housing 25 through the stem 36 and the set screw 37b to the switch contact 37a.

A second switch contact means is provided by a radially or transversely-inwardly-projecting, annular, peripheral rim or ledge 45a of a partition member 45 that is located at an intermediate position with the back housing 42. The partition member 45 of good electrically-conductive material is shown with its centrally-backwardly offset back wall or flange 45b resting on an annular ledge 42c of the housing 42 and as having its annular rim or ledge 45a adapted to be engaged by the first switch contacting means 37a in a "make and break" relationship. Electrical current connection is made to the second switch contact means 45a by a connector means or terminal 50, such as a threaded binding post and washer assembly, which projects through the wall of the housing 42 and into threaded-engagement within the partition member 45. It will be noted that the wall 45b of partition 45 has a central opening therethrough to axially-slidably position the reset or manual push stem 47 and limit the backward position of such stem in cooperation with a front stop or disk-like flange 48 on its front end. The flange 48 is adapted to normally cooperatively engage the back end of the operating stem 36 through the agency of the flattened head of the set screw 37b (see FIGURE 3).

It will be noted that the reset or push stem 47 has a second or back stop flange or projection 48a for engagement with the inner side of a back closure end wall 42b of the housing 42. At this time, the front flange 48 will, as shown in FIGURE 3, be in engagement with the back end of the operating stem 36 (see FIGURE 3), and electrical connection will be made between switch contacts 37a and 45a. This represents the normal back position of the parts of the device when no heat energy is being applied to the part 18 for electrically-energizing the electro magnet 30.

Resilient or spring means is provided within the back housing 42 for normally urging both the operating stem 36 and the reset means or push stem 47 to their back positions, at which time, closed switch contacts 37a and 45a transmit electric current between terminal assemblies 50 and 51 and also, at which time, magnetic contact or hold plate 35 is withdrawn from engagement with the electro magnet 30 (see FIGURE 3). The spring means comprises a forward spiral spring 38 that resists axial compressing force and is operatively-positioned along or about the operating stem 36 to, at its forward end, abut the back end wall of the inner housing 25 and, at its back end, 60 abut the disk 37 carried by the operating stem. The spring means also comprises a second spiral spring 49 that resists axial compressing force and is operatively-positioned along or about the reset or push stem 47 to abut between the back end of the partition part 45 and the front face of the back stop or limit flange 48a.

In operating the device, it will be noted that its normal position is that disclosed in FIGURE 3 when the pilot burner 19 is not lit. To reset the device, the push stem 47 is manually pushed forwardly against the resiliency of the springs 49 and 38 to move the operating stem 36 forwardly and cause the magnet plate or disk 35 to engage the contact faces 30a of the electro magnet 30. Manual force is retained on the outwardly projecting push stem 47 until the burner 19 has generated sufficient heat

in the part 18 to electrically-energize the magnet 30. As long as the heat is maintained, the magnet 30 holds the disk 35 in engagement therewith and the operating stem 36 in its forward position of FIGURE 4. At this time, the manual force on the reset stem 47 will be released and it will then return to the position of FIGURE 5. It will be noted that the switch contacts 37a and 45a are out of engagement and no electrical current flows to the alarm system shown in FIGURE 6.

However, if the gas supplied to the burner 19 should fail or the oxygen supply should become insufficient, such that the flame or heat producing means goes out, then the electric current supplied by the part 18 will cease and the magnet 30 will release the contact or hold disk 35. At this time, the spring 38 will then return the operating shaft 36 from the position of FIGURE 5 to the position of FIGURE 3 to cause current to flow between terminals 50 and 51 and connected electrical lines or leads 50a and 51a to a warning means 55. In FIGURE 6, a suitable source of electric current, such as battery B, is shown connected through the device 10 in such a manner that when the switch contacts of the device are closed, a continuous warning signal will be given to the warning device 55 in the form of an electrically-operated bell or other electrically energized warning means. When the pilot light is not in use, an auxiliary switch 56 in the electric circuit may be opened. It will be noted in FIGURE 6 that the unit 10 is removably-maintained within lower compartment C by a pair of support arms 57 and 58 which are of angle-shape and are removably-secured to a side of the housing part 11 by bolt and nut assemblies 59, and in such a manner, that the reset stem 47 projects below the lower arm 58 and the housing 11 for manual push-in resetting operation.

As to FIGURES 6 and 7, the housing part 11 may be slid backwardly over the inner or positioning part 12 after the latter part has been secured on a structural support or wall. The housing part 11 can thus be readily mounted and dismounted for inspection of the chambers A and B by means of the metal screws 14.

Although the invention has been described from the standpoint of an illustrative embodiment, it will be apparent to those skilled in the art that various changes, modifications, and adaptations may be made without departing from its spirit and scope as indicated by the claims.

I claim:

1. In a device for warning of flame failure having a hollow non-magnetic front housing and employing a thermally-energized electric magnet mounted within a front end portion of the front housing, a magnetic contact plate to be magnetically held in a forward position by the magnet upon an application of heat-induced energy thereto, an operating stem projecting axially backwardly from and supporting the contact plate for moving it into and out of engagement with the magnet, and means at the back end portion of the front housing for slidably-supporting the operating stem to project backwardly therefrom, the improvement which comprises: a hollow back housing having a front open end portion for cooperative mounting with respect to the back end portion of the front housing, said back housing receiving a back end portion of the operating stem therein, a first switch contact means mounted on the back end portion of the operating stem, a second switch contact means within said back housing in cooperative alignment with said first switch contact means, reset means extending backwardly from the back end portion of the operating stem and operatively-mounted within and extending outwardly through a back end portion of said back housing, and spring means within said back housing and cooperating with the operating stem and said reset means for normally urging the operating stem to a back position at which the contact plate is out of engagement with the magnet and said first switch contact means is in closing

engagement with said second switch contact means, and said reset means cooperating with the operating stem for moving it forwardly against the resiliency of said spring means until the contact plate is in engagement with the magnet and said first switch contact means is out of closing engagement with said second switch contact means and for holding the contact plate in engagement with the magnet until the magnet is energized by the application of heat-induced energy to magnetically-maintain said contact plate in engagement therewith.

5 2. In a device as defined in claim 1 wherein an electric alarm system is connected to said switch contact means for warning of flame failure when said switch contact means is closed by de-energization of the magnet and the operating stem is returned by said spring means to its back position.

10 3. A device as defined in claim 1 wherein, said first switch contact means is a conductive disk mounted on the operating stem, and said second switch contact means is a conductive annular abutment projecting radially within said back housing for cooperatively-receiving said conductive disk.

15 4. In a device as defined in claim 3 wherein, said reset means comprises a push stem having a radial projection cooperating with said back housing for limiting the maximum outward movement of said push stem with respect to said back housing; and said spring means comprises, a first spiral spring operatively mounted along the back end portion of the operating stem within the front end portion of said back housing and between the back end portion of the front housing and a front side of said conductive disk, and a second spiral spring operatively positioned along said push stem within the back end portion of said back housing and between a back side of said annular abutment and the back end of said back housing.

20 5. A device as defined in claim 4 wherein said push stem has a front end portion for normally engaging a back end of the operating stem.

25 6. A device as defined in claim 5 wherein said front end portion of said push stem is a position limiting flange.

7. In a device as defined in claim 1 wherein, a second hollow front housing encloses and removably positions the non-magnetic front housing therein and projects backwardly therefrom to endwise-receive the front end portion of said back housing therein, and securing means is carried by the back end portion of said second front housing for removably-securing said back housing in position therewithin.

30 8. In a device as defined in claim 7 wherein, said back housing is a non-conductive material, electrical connector means extends through said back housing to said second switch contact means, the first and second front housings and the operating stem are of electrically conductive metal, said first switch contact means is electrically connected through the operating stem and the first front housing to the second front housing, and electrical connector means is secured to the second front housing.

35 9. A device as defined in claim 1 wherein, a mounting housing is provided for securing to a building member and defines an upper burner compartment and a lower housing compartment for the device, and means is carried by said lower compartment and cooperates with the front housing and said back housing of the device to securely mount the device within the lower compartment.

40 10. A device as defined in claim 1 wherein said first switch contact means is an electrically conductive disk secured on a back end of the operating stem, said second switch contact means is an electrically conductive partition within said back housing and through which said reset means slidably extends, said reset means comprises a push stem having a flange to engage the back end of the operating stem, and said flange is adapted to engage within said partition to limit backward movement of said push stem outwardly with respect to said back housing.

45 11. A device as defined in claim 1 wherein, said first

7
switch contact means is an electrically conductive disk secured on a back end of the operating stem, an abutment is positioned within said back housing, said abutment has an annular peripheral portion comprising said second switch contact means and has a centrally-backwardly offset wall, and said reset means has a front end flange adapted to engage within said offset wall under force exerted by said spring means.
